US00D721338S

(12) **United States Design Patent**
Andre et al.

(10) **Patent No.:** US D721,338 S
(45) **Date of Patent:** ** Jan. 20, 2015

(54) **THERMAL DEVICE**

(75) Inventors: **Bartley K. Andre**, Menlo Park, CA (US); **Jeremy Bataillou**, San Francisco, CA (US); **Brett Degner**, Menlo Park, CA (US); **Jesse Thomas Dybenko**, San Jose, CA (US); **William Francis Leggett**, San Jose, CA (US); **Nicholas Alan Rundle**, San Jose, CA (US); **Mikael Silvanto**, San Francisco, CA (US)

(73) Assignee: **Apple Inc.**, Cupertino, CA (US)

(**) Term: **14 Years**

(21) Appl. No.: **29/424,273**

(22) Filed: **Jun. 10, 2012**

(51) **LOC (10) Cl.** 13-03

(52) **U.S. Cl.**

USPC **D13/179**

(58) **Field of Classification Search**

USPC D13/179; 165/80.3, 104.26, 104.33, 165/122, 151, 185; 257/706, 707, 718-722; 361/695, 697, 700, 702, 704, 709, 710, 361/711, 719

(57) **CLAIM**

The ornamental design for a thermal device, as shown and described.

DESCRIPTION

FIG. 1 is a perspective view of a thermal device showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The drawings include CAD lines that represent contour and not surface decoration.

The broken line showing of the thermal device is for illustrative purposes only and forms no part of the claimed design.

1 Claim, 5 Drawing Sheets
